MOTOR LUBRICATING SYSTEM

Is. Alva Walters, San Diego, Calif.

Application April 26, 1937, Serial No. 139,070

3 Claims. (Cl. 184—6)

This invention relates to rotary machinery, and especially to the means for lubricating same.

The chief object of the invention is to lubricate an engine or motor by applying air pressure to the lubricating means independently of the usual lubrication pump or the like.

Another object of the invention is to provide a lubricating system of this kind which, tho of this improved nature, will nonetheless not be complex or costly and can be applied to an ordinary internal combustion engine.

Another object of the invention is to provide an internal combustion lubricating system which can be either built in with the original engine or be easily applied thereto after construction of the invention.

The other objects, advantages and uses of the invention will be made manifest as this specification proceeds.

With these concepts, objects, and aims in contemplation, the invention comprises the combinations, sub-combinations, elements and features shown in the accompanying drawing, described in the following matter, and included within the scope of the subjoined claims.

In the drawing:

Fig. 1 is a side elevation of an internal combustion engine incorporating the construction of the present invention;

Fig. 2 is a sectional view on line 2—2 of Fig. 1, and

Fig. 3 is an enlarged sectional detail of one of the important parts of the invention.

The structure shown in the drawing comprises an internal combustion engine 1, here shown as of the automobile type, having a compressed air reservoir 2 strapped to the side of its crank case, the reservoir having an outlet valve 3 spring-controlled by a coiled spring 4 and manually operable by the tensile member 5 ending in a handle 6 on the dash-board of the automobile. A hemicylinder or elongated enlargement 7 with an open side is secured by the flanged open side to the side of the crank case and has an air line 8 entering it from the valve 3.

Within the member 7 is located a cylinder 9 supported and anchored at one end by means of threaded engagement with the pipe 8 and near its center, supported rigidly and accurately by means of a cradle 10 carrying a strap 11 for firmly encircling and seizing the cylinder to the cradle in such manner that no reasonable amount of vibration will alter the direction of the center line of the cylinder.

The cylinder also bears an air outlet pipe 12.

Within the cylinder a piston 13 is fitted and carries a plunger 14 which bears at its other end a valve member 15. A piston, 13 is fixed from the distal end of the cylinder and urged towards the air pipe end by means of a helical spring 16 as shown. The distal end of the cylinder bears ports 17 arranged on a circle around the end plate of the cylinder.

The reservoir bears a vertically extending partition 18, which carries a seat 19 for the valve 15. The valve head 15, due to the accurate centering and the rigid support of the cylinder, is compelled to always accurately register with the seat 19 on occasion. The partition 18 bears an outlet opening 20 into a compartment 21 having an inlet aperture 22 connected with the crank case oil level for entrance thru the port 20 into the larger compartment and thru the port 17 into the cylinder 9.

Preferably substantially on the longitudinal center of the lower wall of the reservoir a small sump 23 is provided to depend in a downward direction. At the entrance of the sump is provided a screen filter 24 and interiorly of the sump is provided a uni-directional valve 25 spring-held against a seat 26 and allowing egression only from that portion of the cylinder thru a pipe 27. The pipe 27 pursues the path shown in Fig. 1 to the top of the engine where a branch 28 to an oil filter 29 is provided, the oil filter 29 having an outlet 30 to the crank case oil level. The main line 27 enters the regular lubricating system at the point 31, as shown.

The device is especially useful in priming the lubrication system when the main body of the lubricant happens to be viscous and prone to clog the pipes, as on a cold morning or on high altitudes or due to other circumstances. In any of these cases, by the present invention the prevalent difficulty in securing pump lubrication on starting is overcome by pulling the handle 6 leftwardly, whereupon the valve 3 will be opened to inject compressed air into the cylinder 9, thus forcing the spring-urged piston 13 leftwardly and when it reaches the position shown by the dotted lines, it opens passageway thru the compressed air out thru pipe 12 into the larger compartment, at the same time closing the port 20 by means of the valve 15 accurately and firmly contacting its seat 19. The compressed air is ejaculated thru the pipe 12 above the level of the oil therein, and thus acts downwardly on the top surface of the entire body of oil in the larger compartment forcing some thru screen 24, whence, via pipe 27, it enters the lubricating pas-

sages of the engine and provides sufficient lubrication for starting. The oil may pass thru port 31 either into an oil sump or not, the impetus given by the compressed air impulse being usually 5 sufficient to force it to all parts of the engine.

Any excess lubricant that may be forced in the pipe 27 will by-pass thru pipe 28, thru filter 29 and thence back into the oil sump at point 40.

Various refinements and ramifications of 10 structure shown are contemplated as within the present invention, and it is to be understood that the construction disclosed is merely for purposes of exemplification.

I claim:

- 15 1. In an internal combustion engine having a crank case serving as a reservoir for lubricating fluid and a force-feed lubricating system associated therewith including a line adapted to transfer lubricating fluid from said reservoir to other 20 parts of the engine, means for facilitating and accelerating said transfer which comprises a chamber positioned adjacent said crank case, a partition in said chamber dividing same into a first and a second compartment, said partition 25 having an opening formed therein communicating with both of said compartments, said first compartment having an opening formed in the wall thereof communicating with said reservoir whereby lubricating fluid from said reservoir normally occupies without filling, both of said compartments, said second compartment having an opening formed therein communicating with said lubricating fluid transfer line whereby fluid can 30 pass from said reservoir through said compartments to said line, a compressed air reservoir, a line communicating with said compressed air reservoir and said second chamber, valve means for controlling flow of compressed air in said line, and means for simultaneously closing said opening in said partition and directly admitting compressed air to said second chamber whereby lubricating fluid is forced from said compartment into said lubricating fluid transfer line.
- 35 2. In an internal combustion engine having a crank case serving as a reservoir for lubricating fluid and a force-feed lubricating system associated therewith including a line adapted to transfer lubricating fluid from said reservoir to other parts of the engine, means for facilitating and accelerating said transfer which comprises a chamber positioned adjacent said crank case, a partition in said chamber dividing same into a first and a second compartment, said partition having an opening formed therein communicating with both of said compartments, said first compartment having an opening formed in the wall thereof communicating with said reservoir whereby lubricating fluid from said reservoir normally occupies without filling, both of said compartments, said second compartment having an opening formed therein communicating with said lubricating fluid transfer line whereby fluid can 40 pass from said reservoir through said compartments to said line, a compressed air reservoir, a line communicating with said compressed air reservoir and said second chamber, valve means for controlling flow of compressed air in said line, and means for simultaneously closing said opening in said partition and directly admitting compressed air to said second chamber whereby lubricating fluid is forced from said compartment into said lubricating fluid transfer line.
- 45 3. In an internal combustion engine having a crank case serving as a reservoir for lubricating fluid and a force-feed lubricating system associated therewith including a line adapted to transfer lubricating fluid from said reservoir to other parts of the engine, means for facilitating and accelerating said transfer which comprises a chamber positioned adjacent said crank case, a partition in said chamber dividing same into a first and a second compartment, said partition having an opening formed therein communicating with both of said compartments, said first compartment having an opening formed in the wall thereof communicating with said reservoir whereby lubricating fluid from said reservoir normally occupies without filling, both of said compartments, said second compartment having an opening formed therein communicating with said lubricating fluid transfer line whereby fluid can 50 pass from said reservoir through said compartments to said line, a compressed air reservoir, a line communicating with said compressed air reservoir and the closed end of said cylindrical member, a spring-pressed, normally closed valve interposed in said gas line adapted to control flow of gas therethrough, a spring-pressed piston, slidably mounted in said cylindrical member, normally positioned adjacent the closed end thereof, a valve closure member carried on and actuated by movement of said piston, a valve seat mounted on said partition coincident with the opening formed therein, cooperating with said valve closure, said closure during operation being seated only when said piston is moved from normal position by admission of compressed air into said cylindrical member, a compressed air outlet from said cylindrical member comprising an opening formed in a wall of said member normally obstructed by said piston but opened simultaneously with seating of said closure, and a line leading from said opening to an upper part of said compartment above the lubricating fluid level therein, whereby when said closure is seated, compressed air forces lubricating fluid from said compartment into said lubricating fluid transfer line.

can pass from said reservoir through said compartments to said line, a compressed air reservoir, a line communicating with said compressed air reservoir and said second chamber, valve means for controlling flow of compressed air in said line, and means for simultaneously closing said opening in said partition and directly admitting compressed air to said second chamber whereby lubricating fluid is forced from said compartment into said lubricating fluid transfer line, said means being controlled and actuated by opening of said valve means in said compressed air line.

3. In an internal combustion engine having a crank case serving as a reservoir for lubricating fluid and a force-feed lubricating system associated therewith including a line adapted to transfer lubricating fluid from said reservoir to other parts of the engine, means for facilitating and accelerating said transfer which comprises a chamber positioned adjacent said crank case, a partition in said chamber dividing same into a first and a second compartment, said partition having an opening formed therein communicating with both of said compartments, said first compartment having an opening formed in the wall thereof communicating with said reservoir whereby lubricating fluid from said reservoir normally occupies without filling, both of said compartments, said second compartment having an opening formed therein communicating with said lubricating fluid transfer line whereby fluid can 25 pass from said reservoir through said compartments to said line, a compressed air reservoir, a line communicating with said compressed air reservoir and the closed end of said cylindrical member, a spring-pressed, normally closed valve interposed in said gas line adapted to control flow of gas therethrough, a spring-pressed piston, slidably mounted in said cylindrical member, normally positioned adjacent the closed end thereof, a valve closure member carried on and actuated by movement of said piston, a valve seat mounted on said partition coincident with the opening formed therein, cooperating with said valve closure, said closure during operation being seated only when said piston is moved from normal position by admission of compressed air into said cylindrical member, a compressed air outlet from said cylindrical member comprising an opening formed in a wall of said member normally obstructed by said piston but opened simultaneously with seating of said closure, and a line leading from said opening to an upper part of said compartment above the lubricating fluid level therein, whereby when said closure is seated, compressed air forces lubricating fluid from said compartment into said lubricating fluid transfer line.
